UNITED STATES PATENT OFFICE.

MARGARET ELLEN KELLUM, OF BUFFALO, NEW YORK.

INVALID'S BED.

1,368,211.

Specification of Letters Patent. Patented Feb. 8, 1921.

Application filed October 27, 1919. Serial No. 333,548.

To all whom it may concern:

Be it known that I, MARGARET ELLEN KELLUM, a citizen of the United States, residing at Buffalo, in the county of Erie and 5 State of New York, have invented new and useful Improvements in Invalids' Beds, of which the following is a specification.

This invention relates to a bed for invalids who are so sick that they can not be moved about in the bed without serious injury and relates more particularly to a bed for so called "bed ridden" invalids who are forced to lie practically motionless in a reclined position for a considerable period.

10 The object of the invention is to permit of hygienically caring for such patients during their disability, by providing an improved type of bed bucket or bed pan which may be used without moving the patient 15 from his prone, quiet position in the bed. A further object of the invention is to provide an improved form of sheet or mattress cover to be used in conjunction with said bed bucket and adapted to be readily removed and replaced without unduly disturbing 20 the patient. Further objects and advantages of the invention will be more clearly disclosed in the drawings and following description.

25 In the accompanying drawings: Figure 1 is a diminutive perspective view of the mattress with its plug cushion which are used with my improved invalid's bed. Fig. 2 is a diminutive fragmentary perspective 30 of said mattress and plug cushion. Fig. 3 is a diminutive fragmentary perspective showing said plug cushion replaced by a bed bucket. Fig. 4 is a diminutive perspective 35 of the mattress frame. Fig. 5 is a vertical longitudinal section through the bed taken on line 5—5, Fig. 1. Fig. 6 is a vertical transverse section through the bed taken on line 6—6, Fig. 5. Fig. 7 is a central vertical section through the removable cover of the 40 plug cushion. Fig. 8 is a side elevation of said plug cushion. Fig. 9 is a perspective view of the central slide plate of the mattress frame together with its channel iron slide rails. Fig. 10 is a vertical longitudinal section showing said plug cushion replaced by a bed bucket. Fig. 11 is a similar 45 vertical longitudinal section through the bed showing the supporting stand with its bed bucket partially removed from the bed. Fig. 12 is a perspective of the supporting 50 stand with its bed bucket. Fig. 13 is a

front and rear perspective view of the cover of the bed bucket. Figs. 14 and 15 are perspective views of modified supports for the bed bucket. Figs. 16 and 17 are top plan 60 views of the two coöperating mattress cover sections. Fig. 18 is a top plan of the complete primary mattress cover. Fig. 19 is a top plan of the secondary mattress cover.

Similar characters of reference refer to 65 like parts throughout the several views.

In its general organization, this invention consists of a perforated mattress 20, whose aperture 21 is normally adapted to be closed by a plug cushion 22. Whenever it is desired to use the bed bucket 23 for toilet purposes, a slide supporting plate 24 is moved transversely and the plug cushion 22 removed. Thereafter the bed bucket 23 is dropped into its supporting stand and slid 70 transversely under the bed, the bucket being depressed by the pressure of the foot upon a pedal 25. When the bed bucket has been brought under the aperture 21, the pressure on said pedal 25 is released and said bucket 75 allowed to move vertically upwardly into said aperture 21.

The mattress 20 may be supported upon any suitable frame or "bed springs," the frame shown however, being preferred, comprising two main longitudinal supporting spars 26 arranged longitudinally along each edge of the mattress and connected at their opposite ends by two transversely disposed spars 27 which are arranged adjacent to 90 each end of the mattress. Connected to said spars by suitable tension springs 28 are a pair of rectangular frame sections 30 constructed preferably of resilient metal strips 31 and 42 provided with suitable lacings or 95 wires 33 for evenly distributing the weight of the mattress. Arranged between said frame sections 30 and connected thereto by tension springs 34 is a transversely disposed slide plate 35, which is provided with a large 100 vertical central hole 36 for the accommodation of the plug cushion 22 aforesaid.

Secured to the lower face of said slide plate 35 is a pair of inwardly facing transversely disposed guide or slide rails 37 preferably of channel-iron shape forming upwardly facing runways 38. Adapted to be transversely slid upon said runways is the aforesaid slide supporting plate 24 preferably provided with a downwardly projecting handle 40 at the outer longitudinal end thereof so as to facilitate the movement of

said plate. The plug cushion 22 is adapted to normally rest upon this slide supporting plate so that said cushion may completely fill or plug up the aperture 21 of the mattress. When it is desired to remove said plug cushion 22, the said plate 24 is slid into the dotted line position shown in Fig. 6 and the cushion grasped by a suitable handle-ring 41 and pulled vertically downwardly, 10 said ring 41 being preferably a stiff and comparatively heavy metal ring connected to the lower face of said plug cushion by a flexible canvas strap 42, so as to permit said ring to fold up flat against said lower face of said 15 plug cushion. To facilitate the removal or the insertion of the plug cushion 22, the same is made of conical shape, tapering upwardly, the top face however being substantially flat, so as to make the same flush and even 20 with the top surface of the mattress when the cushion is in place. To prevent the soiling of said plug cushion when being used as part of the mattress proper, the same is preferably provided with a suitable cap or 25 cushion cover 43 which is preferably constructed of non-absorbent material and is preferably provided on its lower edge with suitable hooks 44 which are adapted to be hooked into eyes 45 which are suitably secured to the inclined face of said plug cushion. Said hooks and eyes may however be omitted where the cost is an important factor; the frictional contact between the cushion and mattress being sufficient to hold said 30 cushion cover snugly in place. For sanitary reasons also the conical aperture 21 of the mattress is likewise lined with a rubber or other non-absorbent facing 46, the upper terminal edge of which is provided with an 35 annular inwardly facing horizontal flange 47, which acts to smoothly and evenly cover the joint between the cushion and the mattress and prevents anything from getting caught or pinched in said joint.

40 45 A supporting stand for the aforesaid bed bucket 23 is shown complete in Fig. 12, the same comprising an upper sliding guide plate 48 and a lower bucket supporting plate 50 upon which said bucket is adapted to rest.

50 55 At their corners said two plates are connected together by a plurality of compression springs 51, the same being suitably riveted or brazed at their upper and lower ends respectively, to said plates. A plurality of vertically disposed leg or supporting compression springs 52 are secured at their upper ends to the lower face of the supporting plate 50, their lower ends being provided with suitable rubber wheeled casters or rollers 53. Suspended from the lower face of said supporting plate 50 is a foot or pressure frame 54 provided at its lower end with the pressure plate or foot pedal 25 aforesaid.

60 65 After the plug cushion 22 and the slide plate 24 have been removed, the bed bucket

23 is dropped through a suitable guiding hole 55 in the upper guide plate 48 of the supporting stand, the bucket resting on the lower or supporting plate 50 being preferably centered thereon by a suitable upwardly extending annular flange 56, which receives the lower or narrow end of said bed bucket. The foot is then placed upon the pedal 25 and the same pressed downwardly, permitting the upper or guide plate 48 to be engaged with the runway 38, whereupon the whole supporting stand, together with its bed bucket is moved transversely until said bed bucket comes approximately into position beneath the tapered aperture 21 of the mattress and beneath the large hole 36 of the slide plate 25. The pressure of the pedal 25 is then released, which allows the compression springs to force upwardly the supporting plate 50 and hence also the bed 70 75 80 85 90 95 100 105 110 115 120 125 130 bucket, causing the latter to assume the position shown in Fig. 10. The conical surface of the mattress aperture 21 acts to guide or centralize the bed bucket into proper position, should the supporting band be somewhat out of line with said aperture. The upward movement of said bed bucket is limited by the inwardly facing annular flange 47 aforesaid which contacts with and sanitarily covers the edge of the bed bucket, and the upward movement is also stopped when the upper compression springs 51 have been completely compressed. When it is desired to remove the bed bucket, the foot is again placed and presses upon the pedal 25 and then the laterally extending handle 60, which is fastened to the lower or supporting plate 50 is then seized by the hand and the whole stand slides out from under the bed.

Means are provided also for automatically 105 covering up said bed bucket as the same is being removed from the bed as follows:

A flat bucket cover 61 is provided having a downwardly depending rim 62 there-around which rests around the bucket, such 110 rim being cut away for a portion of its periphery to permit it to be slid over or away from the bucket.

A modified and less expensive form of supporting stand is shown in Fig. 14 in 115 which the supporting leg springs 52 are eliminated as is likewise the automatic cover feature. In this case, the stand has to be lifted into the runways 38, but the general operation is otherwise the same.

A still less expensive form of bed bucket support is shown in Fig. 15, which is more particularly adapted for use in free municipal hospital wards. In this case, the upper and lower plates are rigidly connected by 120 125 130 posts 69 and a hinged drop cover 500 is provided which may be dropped into the dotted position shown and the bucket inserted manually through a suitable hole 550 in the lower or supporting plate. When the bucket 130

is in place, said cover 500 is swung up and secured in place by a suitable catch or latch 150.

Adapted to suit the particular construction of this improved invalid's bed, is a sheet or mattress cover 68, which is constructed in two sections 70 and 700 each of which is provided with a plurality of suitable button holes 71 or other suitable means 10 whereby the same may be secured to the mattress. Each section is provided with a central opening 72 which is arranged to be aligned with the aperture 21 of the mattress.

Each mattress cover section is also provided at one end with a pair of leg or connecting portions 73 extending longitudinally from said opening 72 to the outer edge of said cover section, so that each section may be securely fastened to each of the four corners of the mattress and all unevenness and wrinkling thereby avoided. Formed between said leg portions 73 is a slit 74 which also extends longitudinally from the central opening 72 to the outer edge of the mattress and is sufficiently wide so that the patient may be supported in said slit and between said leg portions, and the removal from the bed of the mattress cover sections being thereby considerably facilitated. 30 When desired an additional mattress cover 75 may be also employed, which may be constructed of a comparatively cheap non-absorbent material and is adapted to be removed from the bed less frequently than the 35 mattress cover sections aforesaid, and may, if desired, be loosely sewed directly to the mattress proper to the flange 47, so as to absolutely prevent any soiling by liquids of the mattress.

40 On the whole, this invention is seen to be

a great boon to those patients who are forced to lie prone in bed for a considerable period, and it may be instrumental even in saving the life of those who are put through terrific agonies when forced to sit up or even 45 move slightly. Normally the upper surface is soft and unbroken and yet whenever required the plug cushion 22 may be very readily removed and the supporting stand 50 with its bed bucket 23 easily slid under 50 the bed, and said bucket elevated into proper position. The odium which attaches to the operation of the device is completely eliminated by the slide cover 63 which automatically either covers or uncovers itself as the 55 case may be. And furthermore the mattress and cushion covers are adapted to easily permit of keeping the bed and patient sanitary and wholesome at all times, without unduly disturbing the patient. 60

I claim as my invention:

1. An invalid's bed comprising a mattress frame provided with a runway, a mattress arranged thereon and provided with a central aperture, a carriage arranged to slide in 65 said runway, and a bucket adapted to be received within said aperture and adapted to resiliently rest on said carriage, said bucket being adapted to be resiliently moved vertically downwardly out of said aperture. 70

2. An invalid's bed comprising a mattress frame provided with a horizontal runway, a carriage arranged to slide on said runway, a supporting plate arranged on said carriage and resiliently forced vertically upwardly relatively thereto, a mattress provided with an aperture, and a bed bucket adapted to rest on said supporting plate and adapted to be received within said aperture. 75

MARGARET ELLEN KELLUM.
